UNITED STATES PATENT OFFICE.

WILSON S. FREESLAND, OF NORFOLK, VIRGINIA.

MULTICONTACT CRYSTAL DETECTOR.

Application filed October 2, 1922. Serial No. 591,904.

This invention relates to multicontact crystal detectors, and the principal object of the invention is to reduce to a minimum the interference caused in the present day crystal radio sets by the "burning out" or losing of the sensitive spot on the crystal.

Another object is to produce a device of this nature wherein a multiplicity of circuits are instantly available for each crystal used.

Another object is to produce a device of this nature which shall be of simple construction, cheap to manufacture, and highly efficient for the purpose for which it is designed.

With these and other objects in view which will become more apparent as this specification proceeds, the invention resides in certain novel features of construction and combination and arrangement of parts, the essential features of which are hereinafter fully described, are particularly pointed out in the appended claim and are illustrated in the accompanying drawing, in which:

Fig. 1—is a top plan view of my multicontact crystal detector.

Fig. 2—is a side elevation of the same, parts being taken away for the sake of clearness.

Fig. 3—is a bottom plan view of the device.

Like characters of reference refer to like parts in all views.

It is well known to radio users that the rectifying crystals have an unknown number of sensitive spots which must be picked or selected by careful adjustment and experiment. After a certain time of continuous use of one spot, it becomes insensitive which necessitates a re-adjustment. Often times the burning out or losing of the sensitive spot will occur in the middle of a message, causing confusion or perhaps the entire loss of the meaning of the message. The present invention contemplates elimination of these difficulties by providing means for instantly switching from one to another of a multiplicity of previously located sensitive spots on the crystal.

Referring to the drawing in detail, 10 represents a base plate which may be of

any suitable insulating material such as hard rubber, and molded to the form shown in the accompanying drawing. The base 10 carries the usual binding posts 11 and 12. 55 The binding post 12 is connected by a wire 13 with one of the adjusting screws 14 which hold the crystal 15 in its adjusted position in the crystal cup 16.

The binding post 11 is connected by a wire 60 17 with a rotary switch 18 having a finger 19 adapted to be moved over a plurality of contacts 20. Connected to each of the contacts 20 is a wire or lead 21 which passes through a respective aperture in the base 65 10 and forward to the crystal cup where it passes vertically upwardly through the base 10 and into the cup 16, forming a plurality of contact points 22.

In use, the operator drops the crystal 15 70 into the crystal cup 16 and then adjusts it by experiment until a plurality of the points 22 touch sensitive spots on the detector. When the device is then operating, and the sensitive spot in use burns out, the operator 75 can rapidly move the switch finger 19 over the various contacts 20 until a new sensitive spot is brought into play, and so quickly and easily that little or nothing of the message will be lost.

While I have described what I deem to be the most desirable embodiment of my invention, I do not wish to limit myself to the exact details of construction herein set forth, nor to anything less than the whole of my 80 85 invention as set forth in the appended claim.

I claim—

A multiple contact detector for radio comprising a rectangular base having an upwardly standing cup formed thereon, a plurality of contacts arranged in an arc about a common center, said base provided with a plurality of openings opening upwardly into said cup, wires attached to said contacts and 90 extending through said openings into said cup, a metal crystal within said cup, and means detachably mounting said crystal within the cup and in non-supporting engagement with said wires.

In testimony whereof I affix my signature.

WILSON S. FREESLAND.
